TRANSMITTING CIRCUIT

Clarence A. Boddie, Wilkinsburg, Pa., assignor
to Westinghouse Electric & Manufacturing
Company, a corporation of Pennsylvania

Application September 16, 1926, Serial No. 135,791

7 Claims. (Cl. 177—352)

My invention relates to transmitting circuits, and it has particular relation to circuits for use in connection with the transmission of carrier currents along metallic channels, such as power lines, trolley wires and the like.

One object of my invention is to provide means whereby high-frequency currents for transmitting intelligence may be successfully carried across breaks in a transmission line.

10 Another object of my invention is to provide means whereby carrier currents may be bypassed around transformer banks and similar apparatus.

Another object of my invention is to provide, 15 in systems of the type described, means whereby high-frequency currents representing messages may be carried around a break in a transmission line without any great loss or diminution in amplitude.

20 Still another and more specific object of my invention is to provide, in carrier-current systems, means whereby the capacitive impedance of a break in the transmission line may be compensated.

25 The successful application of carrier-current transmission along power lines has been very seriously handicapped by the presence in such lines of transformer banks of very high impedance to the frequencies used for the transmission of intelligence. The necessity for the interposition of circuit breakers, disconnect switches and other circuit-interrupting devices has also proved detrimental.

30 In order that there shall be no interruption to the transmission of messages, it is necessary that all unavoidable breaks in the metallic conductor shall be bridged or by-passed by instrumentalities capable of efficiently transferring the carrier current from one side of the break to the other.

35 It is not feasible to merely couple a conductor capacitively to the power line at each side of the break, depending on the capacity between the conductor and the line to carry the high-frequency current, as the impedance of the condenser formed between the line and conductor would be unduly high. I have found, however, that, by making use of the correct amount of inductance, the capacity between the line and the coupling conductor may be made use of to "tune" the coupling in such manner as to obtain substantially zero reactance from line to line, at the frequencies used.

40 In order that a complete understanding of the theory underlying my invention, and the instru-

mentalities involved may be had, attention is directed to the accompanying drawing, and to the following description, wherein

Figure 1 is a perspective view of one of the power-line supporting poles, showing the space relationship existing between the power lines and the coupling antennæ. 5

Fig. 2 is a diagrammatic view of the circuits involved in a preferred form of my invention.

Fig. 3 is a diagrammatic view of an optional 10 form of my invention.

Fig. 4 is a diagram illustrating the reactance relations between the various types of tuned circuits embodying my invention.

Referring specifically to Fig. 1, a plurality of 15 power lines 1, 2 and 3 are supported in spaced relation by a pole 4 and a cross-arm 5 affixed thereto. A second cross-arm 6 is supported on the pole 4 and carries, at its extremities, a plurality of coupling antennæ 7 and 8. A single 20 pole only is shown in the drawing, it being understood, however, that a plurality of poles would be required in actual practice to support an adequate length of antenna.

In Fig. 2, a plurality of power-lines 1, 2 and 3 25 have their electrical continuity interrupted by a series of gaps or disconnect switches 10, 11 and 12, or other apparatus offering high impedance to the carrier-frequencies employed for transmitting intelligence. An antenna 13 is capacitively 30 coupled to one of the power lines and bridges the gap formed by the disconnect switch 10. A second antenna 14 is capacitively coupled to another of the power lines 3, bridging the gap across the disconnect switch 12. Between these two antennæ 35 13 and 14 is connected a circuit comprising an inductor 15, an inductor 16 shunted by a condenser 17 to form a parallel resonant circuit, and another inductor 18.

Although I have shown three power lines for 40 the transmission of polyphase currents, only two of such lines are utilized for signaling purposes. I have accordingly illustrated my invention as applicable to only two of the three lines, it being obvious that it is also applicable to power systems employing only two wires. 45

The entire circuit, comprising the antennæ-power-line capacities and the various inductances, is tuned in a definite manner, which will be explained later. 50

At the present time, it is customary to employ two different high-frequencies in carrier-current communication over power lines, one frequency being used for sending and the other for receiving, both frequencies being modulated by 55

- the signals being transmitted. If there happen to be open disconnect switches in the power lines, or a transformer offering high impedance to the carrier frequencies, considerable difficulty would be experienced in efficiently by-passing the high-frequency currents. It is, accordingly, necessary that the gaps, or the transformer, offering high impedance to the carrier current, be bridged in some manner. Obviously, the gaps cannot be bridged by metallic connections, as such connections would defeat the purpose of the gaps, yet, at the same time, it is imperative to use bridging means offering low impedance to the carrier currents.
- 15 The natural and obvious solution of the difficulty would, at first glance, seem to be merely the use of bridging antennæ, capacitively coupled to the power lines at each side of the breaks. In view, however, of the relatively high voltages now being used in power transmission, the coupling antennæ would have to be spaced well away from the power lines, and the capacitive impedance of this space would be prohibitively high. By my invention, I provide means for nullifying the capacitive impedance of the space between the power lines and the coupling antennæ, effectively tuning the impedance to the frequencies employed.
- 20 Insofar as the carrier currents are concerned, the two sections into which the power lines are cut by the disconnect switches may be considered as having negligible inductance and capacity, the total line impedance at each side of the break being merely resistive in character. In the usual type of power circuit, the line at each side of the break may be considered as replaced by bridging resistors 25 and 26 of from 600 to 800 ohms. Inasmuch as the carrier currents in each line are, at all times, opposite in phase with respect to ground, the line, at each side of the break, may be considered simply as an open circuit on which is impressed an alternating potential and having in series therein a high resistance. The problem, therefore, resolves itself into one of providing a transformer between the two circuits so constructed as to transfer high-frequency energy from the one to the other without unduly high losses.
- 25 It is well known that, when, for a given frequency, the capacitive reactance is equal and opposite to the inductive reactance in a series circuit, the total impedance, neglecting the resistance, is zero. It is also known that, under the same conditions, a parallel circuit offers infinite impedance to currents of the critical or resonant frequency. At frequencies higher than the resonant frequency, the reactance of the series circuit is predominately inductive, while, at lower frequencies, the reactance is mainly capacitive.
- 30 In Figure 4, is shown a set of curves illustrating the manner in which the reactance of series tuned and parallel tuned circuits varies with the frequency. An axis $x-x$ is chosen to represent frequencies, those below the resonant frequency being laid off to the left of a vertical axis $y-y$, while those above the resonant frequency are represented by distances to the right of the $y-y$ axis. Distances along the $y-y$ axis above the $x-x$ axis represent inductive reactance, and those below the $x-x$ axis, capacitive reactance. Assuming a parallel-tuned circuit comprising an inductance and a capacity, the curves A-B and C-D represent the variation in reactance with frequency, the reactance being infinite at the resonant frequency. A curve E-F represents the variation in reactance with frequency for a series tuned circuit, the curve crossing the $x-x$ axis at the resonant frequency. The curves G-H and I-J represent the resultant reactance of a series-tuned circuit in series with a parallel resonant circuit, and it will be noted that there are two points, K and L, respectively, below and above the resonant frequency, at which the total reactance of the circuits is zero.
- 35 If the inductors 15 and 18 are now properly chosen with reference to the antenna-to-power-line capacities to form a series tuned circuit resonant to a frequency half way between the two frequencies used for transmission and reception, and the parallel-tuned circuit, comprising the inductor 16 and the condenser 17, is adjusted to be resonant to this same frequency, the circuit, as a whole, is resonant to the two desired frequencies. Under such circumstances, maximum current will flow in the circuit 13-14 when either frequency is impressed thereon, and the energy transfer from the power lines at one side of the break to the other is also a maximum.
- 40 It is quite difficult to draw analogies in an effort to picture the manner in which the above complex circuit functions. It will help, however, to state that the coils 15, 16 and 18 function as a one-to-one-ratio auto-transformer, and as such, comprise means whereby the signal frequencies may be transferred from one side of the break in the line to the other. By reason of the small capacity existing in the coupling between the antenna and the power lines, the power frequency is efficiently excluded from this by-pass circuit.
- 45 In the event that only a single frequency is employed for both sending and receiving, it is not necessary to provide a by-pass circuit resonant to two frequencies. In the arrangement shown in Fig. 3, a plurality of power lines 1, 2 and 3 have their electrical continuity broken by a plurality of disconnect switches 10, 11 and 12. An antenna 19 is capacitively connected to one of the power lines 1 and is conductively connected through an inductor 21 to the same line 1 at the other side of the break 10. A second antenna 22 is capacitively connected to another power-line 3, and is also conductively connected through an inductor 23 to the line 3 on the other side of the break 12 therein.
- 50 Again, as explained in connection with Fig. 2, the line on one side of the break may be replaced by an equivalent resistance 25, and the line on the other side of the break by an equivalent resistance 26. The circuit comprising the inductor 21 the capacity between the antenna 19 and the power line 1, the resistor, the capacity between the other power line 3 and the antenna 22, and the second resistor 26, is tuned to the carrier-current frequency by means of the variable inductors 21 and 23. The power line and antennæ, being then series-resonant to the signalling frequency, offer substantially no impedance to currents at that frequency, permitting maximum energy interchange between the sections of the line separated by the disconnect switches.
- 55 My system thus provides an extremely efficient circuit for by-passing high-frequency carrier-currents either around a physical break in the power lines or around apparatus which normally offers very high impedance to the frequencies used for signalling. By reason of the fact that my tuning arrangement provides so efficient a path for high-frequency-energy interchange between the power lines and the coupling antennæ,

it is unnecessary to increase the coupling capacity to the point where there is danger from arc-overs and short-circuits. The power necessary for efficient signalling may be greatly reduced from that required when simple by-pass means are used, with a consequent reduction both in the first cost of the transmitting equipment and in the cost of upkeep.

While I have shown and described only a few specific embodiments of my invention, it is apparent that various changes and modifications may be made in the nature and details of arrangement, without departing from the spirit thereof. I desire, therefore, that only such limitations shall be imposed thereon as are necessitated by the prior art or as are indicated by the appended claims.

I claim as my invention:

1. In a power system employing a plurality of sources of signal energy at different signalling frequencies for duplex communication thereover, a plurality of conductors, apparatus interposed between said conductors of a type through which the signalling energy cannot be transmitted and means for by-passing said signalling energy about said apparatus, said means comprising coupling means between said conductors of a type having the property of an electrical impedance that is large for the frequencies of said signalling energy and a plurality of electrical impedances coupled to said coupling means and forming with said coupling means a network of resonant and anti-resonant circuits which network is resonant at a plurality of the frequencies of said signalling energy.
2. In a power system employing a plurality of sources of signal energy at different signalling frequencies for duplex communication thereover, a plurality of conductors, apparatus interposed between said conductors of a type through which the signalling energy cannot be transmitted and means for by-passing said signalling energy about said apparatus, said means comprising coupling means between said conductors of a type having the property of an electrical impedance that is large for the frequencies of said signalling energy and a plurality of electrical impedances coupled to said coupling means and forming with said coupling means a network consisting of a resonant circuit in series with an anti-resonant circuit, which network is resonant at a plurality of the frequencies of said signalling energy.
3. In a power system employing a plurality of sources of signal energy at different signalling frequencies for duplex communication thereover, a plurality of conductors, apparatus interposed between said conductors of a type through which the signalling energy cannot be transmitted and means for by-passing said signalling energy about said apparatus, said means comprising coupling means between said conductors of a type having the property of an electrical capacity, the impedance of which is large for the frequencies of said signalling energy and a plurality of inductors and condensers coupled to said coupling means and forming with the capacity of said coupling

means a network of resonant and anti-resonant circuits which network is resonant at a plurality of the frequencies of said signalling energy.

4. In combination with a power transmission line having at least two line wires, sources of signal energy of two different frequencies for duplex communication thereover, an apparatus of a type interposing a high impedance to said frequencies in each said line wire and means for by-passing said frequencies about said apparatus, said means comprising a reactance element bridging the terminals of each said apparatus, and a connection between said two reactance elements comprising a reactance element of opposite sign to the first-mentioned reactance element in series with two reactances of opposite sign connected in multiple with each other, the two last-mentioned reactances being tuned to constitute an anti-resonant circuit at the same frequency at which the first-mentioned and second-mentioned reactances constitute a series-resonant circuit.

5. In combination with a power transmission line having at least two line wires, sources of signal energy of two different frequencies for duplex communication thereover, an apparatus of a type interposing a high impedance to said frequencies in each said line wire and means for by-passing said frequencies about said apparatus, said means comprising a reactance element bridging the terminals of each said apparatus, and a connection between said two reactance elements comprising a reactance element of opposite sign to the first-mentioned reactance element in series with two reactances of opposite sign connected in multiple with each other, the two last-mentioned reactances being tuned to constitute an anti-resonant circuit at the same frequency at which the first-mentioned and second-mentioned reactances constitute a series-resonant circuit, said resonant frequency lying halfway between the two frequencies first mentioned.

6. In combination with a power transmission line having at least two line wires, sources of signal energy of two different frequencies for duplex communication thereover, an apparatus of a type interposing a high impedance to said frequencies in each said line wire and means for by-passing said frequencies about said apparatus, said means comprising a conductor for each said apparatus capacitatively coupled to the line wires at each terminal of said apparatus, a connection between said conductors comprising inductance in series with an anti-resonant circuit, said inductance and said capacitative couplings being in series resonance at the same frequency at which said anti-resonant circuit is tuned.

7. In combination with a pair of line wires in series with means for imposing two different frequencies and having interposed between them a high impedance to said frequencies, a channel bridging said impedance comprising a capacitance and an inductance in series with each other and with an anti-resonant circuit consisting of a capacitance and an inductance in parallel.

CLARENCE A. BODDIE.
